UNITED STATES PATENT OFFICE.

WILLIAM G. ORTH AND JOHN B. MILLS, OF DAYTON, OHIO, ASSIGNEES TO OHMER FARE REGISTER COMPANY, OF DAYTON, OHIO, A CORPORATION OF NEW YORK.

DRIVING MEANS FOR TAXIMETERS.

Application filed August 10, 1925. Serial No. 49,173.

This invention relates to a driving means for taximeters, and consists of an improvement on the structure shown in the patent to Popp and De Horevitz, 912,728 dated 5 February 16, 1909.

One of the objects of this invention is to remedy such defects so that it will be impossible for the driver to register and charge an amount greater than the passenger should 10 pay for the distance traveled or the time which the taximeter is held in waiting, or both.

The invention further provides an apparatus of the character referred to which 15 shall be comparatively simple in its construction, strong, durable, efficient in its operation, readily interchangeable with the mechanism now in use and comparatively inexpensive to manufacture. The drive for 20 the main drive shaft consists of a gear on the said main drive shaft, which gear is driven by a worm which is at all times in mesh with the gear.

A further object of this invention is to 25 provide means whereby the rearward movement of the vehicle will be registered or recorded as well as the forward movement of the car or other vehicle.

Another object of the invention is to provide 30 a novel resetting means for the main drive shaft of the taximeter.

With the foregoing and other objects in view the invention consists of the novel construction, combination and arrangement of 35 parts hereinafter specifically described and illustrated in the accompanying drawings wherein is shown a preferred embodiment of the invention, but it is to be understood that various changes and modifications can 40 be resorted to which come within the scope of the claims hereunto appended.

In the drawings:

Figure 1 is a side elevation of a taximeter with the casing removed, having an 45 improved driving means incorporated therein.

Figure 2 is a cross sectional plan view on the line X—X of Figure 1 looking in the direction of the arrows.

Figure 3 is an elevation of the opposite side of the taximeter frame showing the resetting mechanism with the parts in "vacant" or "for hire" position, and

Figure 4 is a side elevational view of a 55 part of the structure shown in Figure 3 but

with the parts in the position in which they would be when the flag shaft was in "hired" position.

Referring to the drawings in detail, a shaft 10 is driven from any suitable part of the vehicle by any conventional means. The shaft may be driven, for instance, by a flexible means actuated by the wheel of the car, or it may be driven from the transmission of an automobile. In case the taximeter is carried by a vehicle other than an automobile, it will of course be necessary to drive the shaft 10 from one of the wheels of the vehicle. The shaft 10 is journaled in bearing plate 11 secured by screws 12 or other convenient means to the side of a taximeter 13. The shaft 10 is provided above the bearing plate 11 with a pinion 14, and with a collar 15 below the bearing plate 11.

The pinion 14 is in mesh with a pinion 16 75 rotatably mounted on a shaft 17 journaled in the bearing plate 11 and a second bearing plate 18. The shaft 17 is provided with a collar 19 above the bearing plate 18 and with a pinion 20 below the said bearing plate. An annular collar 21 is rigidly secured to the shaft 17 below pinion 20, which collar serves as a rest or stop for a spring 22 interposed between the collar 21 and a collar 23 splined to the shaft 17 by means of a pin 24. The collar 23 is provided with teeth 25 which together with the teeth 26 on a collar 27 carried by the pinion 16 form a one-way clutch so that as the shaft 10 rotates in one direction the teeth 26 will ride 90 over the teeth 25, but when the shaft 10 rotates in the opposite direction the teeth engage each other so that the shaft 17 is driven by the shaft 10.

The pinion 14 likewise meshes with a pinion 28 on a shaft 29, which shaft carries a pinion 30. Rigidly secured to the shaft 29 is a cam or eccentric 31 and a spring 32 is interposed between said cam and a collar 33 splined on the shaft 29 by means of a pin 34. The collar 33 is provided with teeth 35 adapted to engage the teeth on the collar 35 forming a one-way clutch.

It will of course be understood that the teeth on the two clutches are so arranged and formed that when one clutch is driving, the other clutch is idling. But regardless of which direction the vehicle may be propelled, one or the other of the clutches will actuate its shafts 17 or 29. Interposed between 110

gears 20 and 30 are two idle gears or pinions 36 and 37. Gear or pinion 36 is carried by a stub shaft 38 and is in mesh with the pinions 30 and 37. The pinion or gear 37 is mounted on a stub shaft 39 and is in mesh with the gears 36 and 20. All of the shafts 17, 29, 38 and 39 are supported by means of the bearing plate 18.

It will be noted that the shaft 29 is much longer than shaft 17 and is journaled at its upper end in a bearing plate 40 which is secured to the side face 13 of the meter. The shaft 29 is provided with a collar 41 above the bearing plate 18 and is provided with a collar 42 splined on the shaft 29 by means of a pin 43 projecting through a slot 44 provided in the hub of the collar. It is therefore obvious that the collar 42 may be moved longitudinally of the shaft 29 but any rotation of the shaft 29 will be transmitted to the collar 42. Rotatably mounted on the shaft 29 is a worm 45, which worm carries a clutch collar 46 adapted to be actuated by a clutch collar 47 carried by the collar 42. This clutch may consist of any conventional means, but in the embodiment of this invention as shown herein, we have indicated that the clutch consists of teeth on the collars 46 and 47 which are adapted to be shifted into or out of engagement with each other by means of the bell crank lever 48 hereinafter described.

The worm gear 45 is at all times in mesh with a gear 49 rotatably mounted on the main drive shaft 50. A disc 52 is rigidly secured to the main drive shaft 50 and interposed between the disc 52 and the gear 49 is a ball clutch 51 so that as the gear 49 rotates in one direction the disc and main drive shaft 50 will be actuated, but if the main drive shaft be rotated in the opposite direction the ball clutch would not transmit this motion to the gear 49. This structure is necessary when the clock mechanism (not shown) is driving the main drive shaft 50 faster than the gear 49 is rotated, such as when the vehicle is waiting after being hired or when the vehicle is moving very slowly.

By the structure heretofore described it is obvious that the shaft 29 will be rotated in the same direction regardless of whether the vehicle is being propelled forward or backward, and that when the lever 48 has moved the collar 42 so as to engage the teeth on the collar 47 with the teeth on the collar 46, the main drive shaft will be driven so that fares will be recorded regardless of the direction of motion of the vehicle.

The flag shaft is denoted by the reference character 53, which shaft is provided with a cam section 54 having a cut away part 55 forming a valley. A bell crank lever 56 provided with an arm 57 is actuated by means of a spring 58 so that the arm 57 will be pressed against cam 54 and will enter the

valley 55 when the valley is adjacent the extremity of the arm 57. The bell crank lever 56 is fulcrumed on a pin 60 so that it can freely turn thereon.

The bell crank lever 48 is fulcrumed at 61 and is provided with a pin 62, which pin is engaged by the bell crank lever 56 when the arm 57 enters the valley 55. In the position shown the parts are in "vacant" or "for hire" position, but as soon as the flag shaft 53 is rotated so that the valley 55 is moved beyond the end of the arm, the bell crank lever is rotated anticlockwise and the spring 63 actuates the bell crank lever 48 so as to engage the collar 47 with the collar 46. When, however, the flag shaft is rotated into "vacant" position, as shown, the arm 57 is moved clockwise by means of the spring 58 and the bell crank lever 48 is rotated anticlockwise so as to disengage the collar 47 from the collar 46 by means of the pin 62. When in "vacant" position, therefore, the main drive shaft 50 is not actuated by any movement of the vehicle. When the flag is in "hired" position the main drive shaft is actuated regardless of the direction of movement.

The eccentric 31 actuates a lever 64 fulcrumed at 65. The lever 64 is provided at its lower end with a roller 66 which roller contacts with the periphery of the eccentric 31. Roller 66 is maintained in contact with the eccentric by means of a spring 67 connected to the upper end of the lever and to the casing of the meter. The extreme upper end of the lever 64 is provided with a dog 68 pivoted to the lever at 69, which dog is adapted to actuate a ratchet 70. The ratchet 70 in turn actuates the pitman 71 which actuates a counter to indicate the total number of miles or unit of distance that the vehicle has traveled. The ratchet 70 is provided with a pin 72 adapted to strike a lug 73 on a sliding rod 74, which rod actuates a counter to indicate the number of units of paid mileage which the vehicle has traveled. The sliding rod 74 is provided with a slot 75 through which extends a pin 76 on the bell crank lever 56. When the flag shaft is in "vacant" position the pin 76 engages the end of the slot 75 and moves the rod 74 to the right, as viewed in Figure 1, so that the pin 72 will not move the lug 73 a sufficient distance to actuate the counter. The sliding rod 74 is normally urged toward the left, as viewed in Figure 1, by means of a spring 77. A pin 78 is carried by the side of the meter, which pin limits the movement of the dog 68 so that regardless of how the flexible cable may become distorted the lever 64 cannot rotate the ratchet 70 more than its normal distance.

The important point, however, is not to charge the passenger more than he should pay. By the construction herein disclosed

the main drive shaft cannot be operated more than it should be, regardless of whether or not the cable should become distorted.

- 5 The main driving shaft 50 must be reset after each passenger is discharged or before the passenger boards the vehicle. This is necessary because the main driving shaft 50 operates a cam which in turn operates a lever which controls the registration of the fares. This cam must be in zero position when the vehicle is engaged for otherwise a fare subsequent to the initial fare would be registered before the passenger had travelled
- 10 15 the distance to which he was entitled for the initial fare or had a sufficient waiting time. This structure is not shown in the drawings for the reason that it is very clearly shown in Figure 8 of the said patent to Popp and De Horivitz, above mentioned.

The novel resetting means is shown in detail in Figures 3 and 4 in which the main drive shaft 50 is shown as provided with a disc 79 rigidly secured thereon, which disc has an annular cut away portion 80 extending slightly more than 180° and terminating in shoulders 81 and 82. A disc 83 is loosely mounted on the main drive shaft 50 and carries a pivoted dog 84 which is pressed against the periphery of the disc 79 by means of a spring 85. The disc 83 is provided with a pinion 86, as shown in Figure 4, which pinion is in mesh with the segmental gear 87 carried by a lever 88 pivoted at 89 in the side of the frame. A spring 90 is secured to the lever 88 and to a connecting rod 91. A fulcrumed lever 92 is fulcrumed at 93 and is provided with an end 94 adapted to engage the lever 88 when the flag shaft is in "hired" position and to hold the lever 88 depressed.

The flag shaft 53 is provided with a pin 95, which pin engages a shoulder 96 on a lever 97 when the flag shaft is in the "vacant" or "for hire" position, as shown in Figures 3. However, when the flag is rotated to "hired" position, the pin 95 is rotated beyond the shoulder 96 as is shown in Figure 4, whereupon the spring 98 attached to the upper end of the lever 97 and to the side of the frame pulls the lever 97 on its fulcrum 99 in an anticlockwise direction. The connecting rod 91 is secured to the lever 97 by means of a pin 100 and is provided at its other end with a slot 101 through which extends a pin 102 on the bell crank lever 92. A spring 103 is secured to the pins 100 and 102 so that the pin 102 is normally held at the end of the slot nearest the pin 100. However, when the pin 95 engages the shoulder 96 moving the connecting rod 91 to the right, the spring 103 rotates the bell crank lever 92 clockwise until the point 104 of the lever 92 engages the heart cam 105 which is the cam which con-

trols the resetting of the fare discs not shown. The bell crank lever 92 also carries near its lower end a lug 106 adapted to engage the heart cam 107, which cam is the resetting means for the extra fare discs not shown. The cams 105 and 107 are engaged before the lever 97 has completed its movement, and hence the slot 101 is required.

When the flag shaft is in "vacant" or "for hire" position, the resetting mechanism is as shown in Figure 3. When the flag shaft is rotated to the "hired" position, the pin 95 passes beyond the shoulder 96 and the lever 97 moves to the left, being actuated by the spring 98. The lever 97 moves the connecting rod 91 to the left and rotates the bell crank lever 92 in an anticlockwise direction so that the end 94 of the lever 92 engages the upper surface of the lever 88, rotating the lever 88 on its fulcrum 89 in a clockwise direction against the tension of the spring 90 until the lever is stopped by the pin 112. The segmental gear 87 rotates the pinion 86 in an anticlockwise direction, and the dog 84 rides over the shoulders 81 and 82 without turning the main drive shaft 50. The parts except the shaft 50 are held in this position as long as the flag shaft is in the "hired" position. However, when the flag shaft is rotated to "vacant" position the pin 95 engages the shoulder 96 and moves the lever 97 in a clockwise direction, moving the connecting rod 91 to the right so that the spring 103 pulls the pin 102 to the right and rotates the bell crank lever 92 in a clockwise direction, removing the end 94 from the lever 88. The spring 90 pulls the lever 88 upwards or rotates it in an anticlockwise direction so that the segmental gear 87 rotates the pinion 86 in a clockwise direction, and the dog 84 engages the shoulder 81 moving the main drive shaft 50 in a clockwise direction until the shoulder 82 is adjacent the V shaped lug 108 on the holding dog 109 pivoted at 110. The pin 111 carried by the lever 88 moves the dog 109 toward the main drive shaft 50, and the V shaped lug 108 engages the shoulder 82. When the shoulder 82 is engaged by the lug 108 the main drive shaft is in its reset position. The holding dog 109 is urged away from the disc 52 by means of a spring 113 unless the tension of the spring is overcome by means of the pin 111 when the parts are being reset. As the lever 92 was rotated clockwise the point 104 engaged the heart cam 105, and the lug 106 engaged the heart cam 107 resetting the fare and extra discs. It will be noted that the lever 88 is provided with a hardened bearing plate 114, which bearing plate is approximately twice the width of the lever 88 or of a suitable width to prevent the end 94 of the lever 92 from sliding off the lever 88 in case the lever 92 should become slightly bent through hard usage.

Without further description it is thought that the features and advantages of this invention will be readily apparent to those skilled in the art, and it will be understood that changes in the form, proportion and construction may be resorted to without departing from the spirit of the invention and the scope of the appended claims.

We claim:

10. 1. In a taximeter, a shaft, a pinion thereon, a second shaft, means whereby the second shaft is driven by the said pinion regardless of the direction of motion of the vehicle, a main drive shaft, and means whereby said second shaft may be operatively connected with or disconnected from said main drive shaft.
20. 2. In a taximeter, a shaft, a gear thereon, a second shaft, a gear thereon in mesh with the first mentioned gear, a one-way clutch operatively connecting the second shaft with its gear, a third shaft, a gear thereon in mesh with the first mentioned gear, a one-way clutch operatively connecting the third shaft with its gear, second gears on the second and third shafts, an even number of meshing idle gears operatively connecting the second gears on the second and third shafts so that the second shaft is rotated in one direction regardless of the direction of rotation of the first mentioned shaft, a main drive shaft.

and means operatively connecting said second shaft with said main drive shaft.

3. In a taximeter, a shaft, a pinion thereon, a second shaft, means whereby the second shaft is driven in one direction by the said pinion regardless of its direction of rotation, a main drive shaft, and means whereby said second shaft may be operatively connected with or disconnected from said main drive shaft.

4. In a taximeter, a main drive shaft, a flag shaft, a pinion and a disc loosely mounted on said main drive shaft, a disc rigidly secured to the main drive shaft and provided with a cut away portion forming shoulders, means whereby said pinion is rotated in one direction when the flag is moved from "vacant" to "hired" position, and in the opposite direction when the flag shaft is moved from "hired" to "vacant" position, a dog carried by said first mentioned disc adapted to engage with one of said shoulders when the flag shaft is moved from "hired" to "vacant" position, and means to limit the movement of said main drive shaft when the flag shaft is being rotated from "hired" to "vacant" position.

In testimony whereof we affix our signatures.

WILLIAM G. ORTH.
JOHN B. MILLS.
